Primary Examiner — Susan Bennett Hattan*Assistant Examiner* — Marie Fast Horse(74) *Attorney, Agent, or Firm* — Hitchcock Evert LLP(57) **CLAIM**

The ornamental design for a blower assembly, as shown and described.

DESCRIPTION

FIG. 1 is a perspective view from the top-right of the blower assembly;

FIG. 2 is a back view thereof;

FIG. 3 is a front view thereof;

FIG. 4 is a left side view thereof;

FIG. 5 is a right side view thereof;

FIG. 6 is a top view thereof; and

FIG. 7 is a bottom view thereof; and,

FIG. 8 is a perspective view from the top-left thereof.

The broken lines depict parts of the blower assembly that form no part of the claimed design.
